J. W. WRIGHT.

PICTURE HOOK.

APPLICATION FILED NOV. 18, 1918.

1,313,366.

Patented Aug. 19, 1919.

UNITED STATES PATENT OFFICE.

JOHN W. WRIGHT, OF TORONTO, ONTARIO, CANADA.

PICTURE-HOOK.

1,313,366.

Specification of Letters Patent.

Patented Aug. 19, 1919.

Application filed November 18, 1918. Serial No. 263,040.

To all whom it may concern:

Be it known that I, JOHN W. WRIGHT, a citizen of the Dominion of Canada, residing at Toronto, in the county of York, Province 5 of Ontario, Canada, have invented certain new and useful Improvements in Picture-Hooks; and I do hereby declare the following to be a full, clear, and exact description of the invention, such as will enable others 10 skilled in the art to which it appertains to make and use the same.

This invention relates to new and useful improvements in devices for hanging pictures.

15 One object of the present invention is to provide a novel and simple device which is arranged to be secured to the back of the frame of the picture whereby the picture can be more easily and accurately adjusted to 20 the proper height on the wall, and also at the desired angle to the wall, as well as to the proper level.

Another object of the present invention is to provide a novel and improved device of 25 this character which is preferably formed from wire and which is so constructed that it will be very strong and the several hooks thereof prevented from bending outwardly when the weight of the picture is suspended 30 therefrom.

Other objects and advantages will be apparent from the following description when taken in connection with the accompanying drawing.

35 In the drawing:

Figure 1 is a side elevation of a picture in proper hanging position, and equipped with my improved hook members.

Fig. 2 is a rear elevation of one portion 40 of the picture showing one of the devices in elevation.

Fig. 3 is an enlarged rear elevation of the device looking from the side opposite to that of Fig. 2.

45 Fig. 4 is a transverse sectional view taken on the line 4—4 of Fig. 3.

Referring particularly to the accompanying drawing, 10 represents the frame of the picture to which my invention is secured. 50 Secured to the rear face of each of the end portions of the frame is a wire member 11 which is peculiarly constructed to perform the functions of the present invention. As

the two members 11 are identical in construction a description and illustration of 55 one is sufficient.

The wire member is bent outwardly and upwardly, as shown at 12, and thence downwardly, as at 13, whereby one side of a downwardly directed hook is formed. From the 60 outer end of this side of the hook the wire is extended backwardly into the same form as the hook just described, as shown at 14, the said portion being doubled on itself, as at 15, behind the portion 12, the wire being 65 then continued a short distance upwardly where it is again treated as before described, to provide another hook 16. This is repeated as many times throughout the length of the wire as desired to produce the desired 70 number of hooks. At each end of the wire there is formed an eye for the reception of the screw 17 by means of which the device is attached to the back of the frame. The eyes are shown at 18. The ends of the picture 75 wire 19 are formed with the loops 20 which are engaged with the desired hooks at both sides of the picture frame.

Attention is particularly called to the arrangement of the portions 15 behind the portions 12. Upon an inspection of Fig. 1 it will be seen that when stress is placed on the hooks, by the weight of the picture on the wire, there will be no outward bending of the hooks, because of this arrangement above 85 named. The portions 15 will be pressed against the portions 12 of the wires of the two devices, whereby a strong and durable 90 device is produced. By transferring the loops of the wire 20 from one to another of the hooks, the proper angle of the picture with respect to the wall can be easily obtained, and by interchangeably engaging the loops with the various hooks at one side of the picture, the proper level of the picture 95 can be obtained.

What is claimed is:

1. A picture adjusting and supporting device including a wire member having a longitudinal series of hook portions for engagement by the loops at the ends of a picture wire, said hook portions being formed with bracing means engaging behind the main portions of the wire of the member. 100

2. A picture supporting and adjusting device formed from a single length of wire and 105

including a longitudinal series of hook members bent outwardly from the wire and directed upwardly in approximate parallel relation with the body of the wire, each of said hook members being connected to the body of the wire by a looped portion lying behind the body of the wire and serving to brace the stems of the hooks against

outward bending under the weight of a picture.

In testimony whereof, I affix my signature, in the presence of two witnesses.

JOHN W. WRIGHT.

Witnesses:

GEO. WRIGHT,
JOSEPH P. GEDDES.
